CONSOLE FOR COMPUTING MACHINE

Elmer J. Stoltz, Alameda County, Calif., assignor to
Friden, Inc., a corporation of California

Filed Dec. 28, 1959, Ser. No. 58,837

Term of patent 14 years

(Cl. D26—5)

FIG. 1

FIG. 2

FIG. 1 is a perspective view showing the front-, left-, and top-facing parts of a console for a computing machine embodying the design of my present invention;

FIG. 2 is a perspective view showing the front-, right-, and top-facing parts thereof; and

FIG. 3 is a perspective view thereof as seen from the upper-left-rear.

The dominant features of my design reside in those positions shown in full lines in the drawings.

I claim:

The ornamental design for a console for a computing machine, as shown and described.
